[57] **CLAIM**

The ornamental design for a disc player combined with radio, as shown and described.

DESCRIPTION

FIG. 1 is a perspective view of a disc player combined with a radio showing my new design;

FIG. 2 is a top plan view thereof;

FIG. 3 is a left side elevational view thereof;

FIG. 4 is a front elevational view thereof;

FIG. 5 is a right side elevational thereof;

FIG. 6 is a rear elevational view thereof;

FIG. 7 is a bottom plan view thereof; and,

FIG. 8 is a perspective view thereof, wherein the lid portion is in the open position. The portion in broken lines showing the insides of the disc player combined with the radio are for illustrative purpose only and forms no part of claimed design.

The portions of the inside of the disc player combined with a radio which are not visible in FIG. 8 form no part of the claimed design.
